UNITED STATES PATENT OFFICE.

JOHN CARNES, OF YOUNGSTOWN, OHIO, ASSIGNOR OF TWO-THIRDS TO JOHN WALTERS AND ANDREW H. MIDDLETON, OF SAME PLACE.

RAILWAY SWITCH-ROD.

SPECIFICATION forming part of Letters Patent No. 518,020, dated April 10, 1894.

Application filed December 26, 1893. Serial No. 494,726. (No model.)

To all whom it may concern:

Be it known that I, JOHN CARNES, a citizen of the United States, residing at Youngstown, in the county of Mahoning and State of Ohio, 5 have invented certain new and useful Improvements in Railway Switch-Rods; and I do hereby declare the following to be a full, clear, and exact description of the invention, such as will enable others skilled in the art to which 10 it appertains to make and use the same, reference being had to the accompanying drawings, which form part of this specification.

My invention relates to that class of switch-rods used to connect the switch-rails together 15 so that they move simultaneously and equally in the shift of position, and its object is to provide such a rod, that, applied either in a stub, split, or interlocking switch, is, without the use of spikes, bolts, rivets, or clamps, 20 readily attached to and detached from the rails, and that in place is adjustable to the exact width of the track, and is not in the way of putting in new cross-ties when occasion may require. I accomplish this object 25 by the switch-rod hereinafter described and illustrated in the drawings, in which—

Figure I is a side view of my switch-rod R in place in sections of rails as in use. Fig. II is an enlarged view of a portion from an outer 30 end of the same. Fig. III is an end view of the same, showing in transverse form the head h. Fig. IV is a cross section view of a railroad rail showing in dotted lines the aperture a therethrough; and Fig. V is a side view of a 35 portion of a railroad rail showing the same.

Parts are indicated by letters and similar letters refer to similar parts in all views.

It will be seen that my switch-rod R is in the two parts r r, which I term sectional rods, 40 similar in all respects, except that the screw threads appearing on their respective inner ends are oppositely trending spiral ridges, so that when the parts are united by the turnbuckle b, as shown at Fig. I, they may be forced

45 to or from each other, extending or diminishing the length of the rod R thus formed. Each sectional rod r is preferably round and of suitable size, having upon its outer or rail end the collar formed enlargement or boss b, outside 50 of which appears the neck n which is a con-

tinuation of the rod, and upon the outer end appear the opposite rectangular flanges forming the head h. The neck n is of length equivalent to the breadth of the web of the rail, in the aperture a of which it rests when in place. 55 Suitably inward from the boss b to escape the flange of the rail and no more, the rod r curves downward so that the main body of the rod when in place is below the horizontal plane of the neck n, for a purpose that will presently 60 appear. The turnbuckle t is the usual turnbuckle having the openings at the opposite ends screw threaded by oppositely trending spiral grooves. A turnbuckle in sleeve form to protect the threads, and having an exteriorly 65 angular part for a wrench, I deem to be preferable.

At a suitable location upon that which is the lower portion of the rod when the same is in place appears the lug or ear e, for a means 70 of attaching the connecting rod. The aperture a formed in the rail is in form the same as the transverse form of the head h, the portion, however, corresponding to the flanges being on horizontal lines. It is sufficiently 75 larger than the head h that the latter may pass through it when brought to the necessary position to do so. It will be seen that when my switch rod R is formed by uniting the sectional rods r r, as indicated, the head 80 h may be passed through the aperture a of one switch-rail, and, the rod then being suitably shortened by means of the turnbuckle or the spread of the rails asunder, similarly 85 passed through the aperture a of the other switch-rail, and that upon being released from grasp, the main body of the rod drops downward by reason of the curves described, locking the rod to the rails, which position is maintained by gravity, and that by means of the 90 turnbuckle t the rails may be adjusted to the exact distance from each other that is required.

My invention will now be understood and its usefulness appreciated.

I am aware that a straight switch-rod formed 95 of two similar parts united by a turnbuckle and secured to the rail by clamps, and also that rods to unite railroad rails to keep them from spreading and attachable to the rails by means of heads on the rod ends passing 100

through the webs of the rails and locking upon their outer sides, are known, but I am not aware that my switch-rod *R* in combination with switch-rails, having the apertures *a* as above described was ever known or used until my invention thereof.

What I claim is—

The switch-rod *R*, formed of the two similar rods *r r*, each oppositely screw threaded upon the inner end and united by the turnbuckle *t*, provided with the apertured lug or ear *e* upon the under side, curved downward near the outer end and having outward from the curved portion the fixed collar or boss *b*, out-

side of which appears the neck *n* terminating in two opposite rectangular flanges forming the head *h*, in combination with two opposite switch-rails each having through the web the aperture *a*, in form similar to the transverse form of the head *h* of a rod *r*, all substantially as described and for the purpose expressed.

In testimony whereof I hereunto affix my signature in the presence of two witnesses.

JOHN CARNES.
